PLUGGABLE ELECTRONIC MODULE OR SIMILAR ARTICLE

Thomas O. Gephart, Hawthorne, and Theodore H. Abrahams, Huntington Beach, Calif., assignors to Hoffman Electronics Corporation, a corporation of California

Filed Mar. 29, 1963, Ser. No. 74,191

Term of patent 14 years

(Cl. D26—1)

FIGURE 1 is a front top and right end isometric view of a pluggable electronic module or similar article, showing our new design, the rear being substantially a mirror image thereof;

FIGURE 2 is a left end elevational view;

FIGURE 3 is a right end elevational view; and

FIGURE 4 is a bottom plan view, to a reduced scale.

The broken line showing of electronic components mounted within the module are for illustrative purposes only.

The essential features of my new design are shown in full lines in the drawing.

We claim:

The ornamental design for a pluggable electronic module or similar article, substantially as shown and described
